UNITED STATES PATENT OFFICE.

JULIUS HERRIET, OF NEW YORK, N. Y., ASSIGNOR TO DAVID WOLFE BRUCE,
OF SAME PLACE.

DESIGN FOR A FONT OF PRINTING-TYPES.

SPECIFICATION forming part of Design No. 12,003, dated October 26, 1880.

Application filed August 20, 1880. Term of patent 14 years.

To all whom it may concern:

Be it known that I, JULIUS HERRIET, (assignor to DAVID WOLFE BRUCE,) of the city, county, and State of New York, have invented and produced a new and original Design for a Font of Printing-Types, of which the following is a specification.

The nature of my design is clearly shown in the accompanying typographic impressions, to which reference is made; and it consists of a heavy letter of the class known as "church text," shaded to a lighter line.

The top and bottom portions of the letters are concaved, as shown, and the letters B, D, F, H, I, K, L, N, P, R, T, U, and V are concaved upon the left of the up and down portion. The up and down portion of the A upon the right is concaved. The heavy ball termina-

nation is found in the letters B, C, F, H, J, L, M, N, P, R, S, T, and Q, as shown. 20

In the symbols and figures the motive of the design is preserved, the & and the interjection and interrogation points being provided with the concaved top line, and the concaved lines are found above and below the figures 2, 3, 4, 5, 6, 7, 8, 9, and 0, and in the dollar and pound marks. 25

Having now set forth my invention, what I claim as new is—

The design for a font of printing-types, substantially as shown and described. 30

JULIUS HERRIET.

In presence of—

A. SIDNEY DOANE,
WILLIAM V. HICKS.
